LIQUID SPRAY APPARATUS

John B. Lyman, Minneapolis, and Wallace E. Lind, Anoka, Minn., assignors to Whirlpool Corporation, a corporation of Delaware

Filed Sept. 19, 1961, Ser. No. 139,114

7 Claims. (Cl. 134—176)

This invention relates to spray devices and in particular to moving-path spray devices.

In apparatus such as dishwashers, lawn sprinklers, container cleaners and the like it is desirable to provide a spray issuing in a moving path so as to deliver the liquid to substantially all portions of a preselected space or area. The present invention is concerned with a new and improved moving-path spray device providing improved functioning in such apparatus.

Thus, a principal feature of the present invention is the provision of a new and improved spray device.

Another feature of the invention is the provision of such a spray device having a simple, economical construction while yet providing an improved moving-spray operation.

A further feature of the invention is the provision of such a spray device wherein a rotatable deflector is water-buoyed, providing improved trouble free operation.

Still another feature of the invention is the provision of such a spray device adapted for use in apparatus such as dishwashers for providing improved washing liquid distribution to the upper portion of the washing space.

Other features and advantages of the invention will be apparent from the following description taken in connection with the accompanying drawings wherein:

FIGURE 1 is a vertical diametric section of the dishwasher provided with a spray device embodying the invention;

FIGURE 2 is an enlarged fragmentary vertical section taken substantially along the line 2—2 of FIGURE 1;

FIGURE 3 is a further enlarged horizontal section taken substantially along the line 3—3 of FIGURE 2;

FIGURE 4 is a horizontal section taken substantially along the line 4—4 of FIGURE 2; and

FIGURE 5 is a perspective view of the deflector of the spray device.

In the exemplary embodiment of the invention as disclosed in the drawings, a dishwasher generally designated 10 is shown to comprise an outer enclosure 11 within which is mounted a tub 12 having a bottom 13 spaced above the bottom wall 14 of the enclosure 11. A lower basket 15 is disposed within the tub 12 adjacent bottom 13 and an upper basket 16 is disposed within the tub adjacent the upper end 17 thereof. Washing liquid passing downwardly through a screen 18 to a sump 19 is pumped, by means of a pump 20 driven by an electric motor 21, upwardly through a hose 22 to a spray arm 23 rotatably mounted on a hub 24 fixedly secured to a drawn portion 25 of the tub bottom 13. The spray arm is provided with a plurality of upwardly opening ports 26 from which the washing liquid issues in the form of a forceful jet-like stream so that as the spray arm revolves, the washing liquid is forceably delivered to substantially all portions of the space within the tub 12. Illustratively, the pump 20 may be arranged to deliver approximately 31 gallons per minute at a head of 25 feet through the spray arm 23.

To provide an improved delivery of the washing liquid to the upper portion of the space within tub 12, a second spray device generally designated 27 is mounted on the upper end 28 of a tubular duct 29 fixedly secured to stationary hub 24. A portion of the washing liquid delivered from pump 20 is diverted to pass upwardly through duct

2

29 by means of a diverter 30 extending to within the lower end 31 of the duct 29. As best seen in FIGURE 1, the spray device 27 is disposed at the bottom of the upper portion of the space within tub 12 adjacent upper end 17 to deliver the washing liquid directly to this portion of the space.

Referring now more specifically to FIGURES 2 through 5, the spray device 27 may be seen to comprise a hub generally designated 32 having a tubular lower end portion 33 fixedly fitted to the upper end 28 of the duct 29, a tubular lower mid-portion 34 having a slightly reduced inner diameter and defining at its lower end an annular radial shoulder 35a abutting the upper end of the duct, an inturned upper mid-portion 35, and a tubular inwardly spaced upper end portion 36 having a closed upper end wall 37. Upper mid-portion 35 defines an upwardly facing, annular radial surface 38, and the lower end of portion 36 defines a plurality of flow passages 39 opening at their upper ends vertically through surface 38 and communicating at their lower ends with the space 40 within the hub 32. The upper part of upper end portion 36 is provided with a plurality of flow passages 41 opening radially outwardly into the annular space 42 circumjacent the end portion 36 and communicating inwardly with the internal space 40 of the hub 32.

An annular deflector 43 is mounted for free rotation on the upper end portion 36 of the hub in overlying relationship with surface 38. As best seen in FIGURE 5, deflector 43 defines a plurality of vanes 44 each curving from a base portion 45 extending substantially in a transaxial plane perpendicular to the axis of the deflector to a tip portion 46 extending at a substantial angle thereto, herein over 45° relative to the transaxial plane.

Spray device 27 further includes a cup-shaped cap 47 provided with a transverse end portion 48 facially secured to the end wall 37 of the hub by suitable means such as screw 49. The downturned side wall 50 of the cap 47 defines the radially outer boundary of annular space 42 and extends downwardly to slightly above the mid-portion 45 of the deflector 43.

As indicated briefly above, a portion of the washing liquid delivered from pump 20 is directed by diverter 30 upwardly through duct 29. A portion of this washing liquid is directed through flow passages 39 to strike the underside of deflector portion 45 thereby lifting the deflector to space it upwardly of the hub portion 35 thereby effectively eliminating frictional engagement of the deflector with the hub portion 35. A second portion of the washing liquid delivered from duct 29 passes outwardly through flow passages 41 into annular space 42 wherein it is redirected by the cap 47 to flow substantially vertically downwardly and strike the upper surface of the deflector mid-portion 45. This portion of the washing liquid then flows radially outwardly to pass between the deflector and the lower end of the cap portion 50 and in doing so impinges on the vanes 44 thereby causing the deflector to rotate about the axis of the spray device.

As shown in FIG. 2, the washing liquid passing over the portion of each vane extending generally transaxially (the leftward illustrated vane portion) issues from the spray device generally in the transaxial plane. The portion of the washing liquid impinging on the most curved portion of each vane (the rightward vane portion in FIG. 2) is deflected thereby at a substantial angle to the transaxial plane, and in the illustrated embodiment at an angle of over 45° thereto. Thus, the path of the washing liquid issuing from the spray device taken in any selected axial plane (e.g., the plane of the paper) varies from a path generally parallel to the transaxial plane (i.e., a plane perpendicular to the plane of the paper and the axis of the deflector) to a large angle to the transaxial plane as the deflector spins around on the hub.

Thus, in effect, each vane causes the tilted sheet-like configuration of the washing liquid issuing outwardly thereover to move generally conically about the vertical axis of the spray device while each droplet of the washing liquid moves substantially rectilinearly in an axial plane. The resultant substantially complete distribution of the issuing washing liquid through the space within the upper portion of the tub 12 effectively assures full, thorough washing of the elements therein.

The spray device 27 may be utilized in other apparatus, such as container cleaning apparatus or sprinklers. The improved uniform distribution of the liquid provided by the spray device assures uniform delivery to the circumjacent space and the limitation of the movement of the individual droplets substantially to axial planes assures effectively maximum utilization of the liquid pressure in the outward force of the spray. The buoying of the deflector by the liquid passing upwardly through the passages 39 against the underside thereof effectively assures long, trouble-free operation as friction is effectively minimized. Further, the utilization of the outwardly issuing water itself to effect the rotation of the deflector eliminates the need for driving mechanism, greatly simplifying the associated structure and thereby effectively minimizing the cost of the apparatus.

Having described our invention as related to the embodiment shown in the accompanyings, it is our intention that the invention be not limited by any of the details of description, unless otherwise specified, but rather be construed broadly within its spirit and scope as set out in the accompanying claims.

The embodiment of the invention in which an exclusive property or privilege is claimed as defined as follows:

1. In a washer apparatus having means defining a washing space including a lower and an upper portion, and means in the lower portion for forcibly distributing washing liquid through said space to wash elements such as dishes and the like therein, means for forcibly distributing washing liquid through said upper portion comprising: a fixed duct having an outlet end at the bottom of the upper space portion for delivering washing liquid under pressure upwardly thereto; deflecting means movably carried by said duct end; and means for directing washing liquid delivered through said duct against both the top and the bottom of the deflecting means to support the deflecting means on the liquid being delivered, said deflecting means directing the washing liquid delivered through said duct end onto the top thereof into a path vertically reciprocating through said upper space portion.

2. A spray device comprising: a hub having a first portion defining an upper transverse surface, and a second portion extending upwardly therefrom, said surface extending circumjacent the inner end of said second portion, said first portion defining a first flow passage opening through said surface for directing liquid upwardly therefrom, said second portion defining a second flow passage for directing liquid to the space adjacent said second portion; a deflector extending rotatably around said second portion and transversely across said space adjacent said surface to be supported spaced above said surface by liquid passing upwardly through said first flow passage, said deflector defining a vane; and means directing liquid from said second flow passage downwardly toward said surface to impinge on said vane and propel the deflector rotatively about the axis of said second portion of the hub and to issue laterally away from said space in a spray path, the rotation of said deflector vane causing reciprocation of said spray path in a plane of said axis.

3. The spray deflector of claim 2 wherein said liquid directing means comprises a cup-shaped member co-

axially secured to the outer end of said second portion and opening downwardly toward said surface.

4. A spray device comprising: a hub having a first vertical cylindrical portion defining an upper, planar, transverse surface, and a second cylindrical, diametrically reduced portion extending coaxially upwardly therefrom, said first portion defining a plurality of first flow passages each opening through said surface parallel to the axis of the hub for directing liquid upwardly therefrom, said second portion defining a plurality of second flow passages for directing liquid radially outwardly therefrom to the circumjacent space; a deflector extending rotatably around said hub second portion and transaxially across said space adjacent said surface to be supported spaced from said surface by liquid passing outwardly through said first flow passage, said deflector defining a plurality of circumferentially related vanes; and means directing liquid from said second flow passages to impinge downwardly on said vanes and propel the deflector rotatively about the axis of said hub second portion and to issue laterally away from said space in a spray path, the rotation of said deflector causing said vanes to reciprocate said spray path parallel to the axis of said hub.

5. The spray device of claim 4 wherein said liquid directing means comprises a cap having a transverse end portion secured to the outer end of said hub second portion, and a tubular portion extending concentrically of said hub second portion and downwardly from said end portion to adjacent said deflector.

6. The spray deflector of claim 4 wherein said vanes are curved from a plane substantially perpendicular to said axis to over 45° away from said plane to reciprocate said spray path through a corresponding angle.

7. For use in a washing apparatus having means defining a washing space including a lower and an upper portion, and means in the lower portion for forcibly distributing washing liquid through said space to wash elements such as dishes and the like therein, means for forcibly distributing washing liquid through said upper portion comprising: a fixed duct extending vertically in the washing space including an outlet hub at the bottom of the upper spaced portion, said hub having a first portion defining an upper transverse surface, and a second portion extending upwardly therefrom, said surface extending circumjacent the inner end of said second portion, said first portion defining a first flow passage opening through said surface for directing liquid upwardly therefrom, said second portion defining a second flow passage for directing liquid to the space adjacent said second portion; a deflector extending rotatably around said second portion and transversely across said space adjacent said surface to be supported spaced above said surface by liquid passing upwardly through said first flow passage, said deflector defining a vane; and means directing liquid from said second flow passage downwardly toward said surface to impinge on said vane and propel the deflector rotatively about the axis of said second portion of the hub and to issue laterally away from said space in a spray path, the rotation of said deflector vane causing reciprocation of said spray path in a plane of said axis.
